US0D1038008S

(12) **United States Design Patent** (10) Patent No.: **US D1,038,008 S**
(45) Date of Patent: ** Aug. 6, 2024

(54) **ELECTRIC BICYCLE BATTERY PACK**

(71) Applicant: **Shenzhen Vanpowers Intelligent Technology Co., Ltd**, Shenzhen (CN)

(72) Inventors: **Peng Liang**, Shenzhen (CN); **Yanxing Yu**, Shenzhen (CN)

(**) Term: **15 Years**

(21) Appl. No.: **35/517,574**

(22) Filed: **May 29, 2023**

(80) **Hague Agreement Data**

Int. Filing Date: **May 29, 2023**

Int. Reg. No.: **DM/229558**

Int. Reg. Date: **May 29, 2023**

Int. Reg. Pub. Date: **Jun. 23, 2023**

(57) **CLAIM**

The ornamental design for an electric bicycle battery pack, as shown and described.

DESCRIPTION

1. Electric bicycle battery pack

1.1 : Perspective

1.2 : Right

1.3 : Left

1.4 : Front

1.5 : Back

1.6 : Top

1.7 : Bottom
